UNITED STATES PATENT OFFICE.

LOVELL A. HERSH, OF DAYTON, OHIO, ASSIGNOR TO HARRY BOHN, OF DAYTON, OHIO.

CLOTHES-WASHING MACHINE.

Application filed February 16, 1929. Serial No. 340,803.

This invention relates to a clothes washing machine and is in the nature of an improvement on the clothes washing machine shown and described in the application filed 5 by Charles Roberts, on July 19, 1928, Serial No. 293,845.

One object of the invention is to provide in a machine of the type shown in the above mentioned application a gear box of a 10 strong durable character which may be made in one piece and which will be of such a character that the driving mechanism may be easily inserted and assembled therein.

A further object of the invention is to 15 provide in such a machine improved means for connecting the agitator with its shaft.

A further object of the invention is to provide an improved mechanism for operating the clutch which connects the agitator 20 with the source of power.

Other objects of the invention will appear as the mechanism is described in detail.

In the accompanying drawings Fig. 1 is 25 a vertical sectional view taken centrally through a machine embodying my invention, with the pedestal in elevation and partly broken away; Fig. 2 is a plan view of such a machine, partly broken away and showing the agitator in transverse section; Fig. 30 3 is a sectional view taken on the line 3—3 of Fig. 1, through the gear box; Fig. 4 is a vertical section taken on the line 4—4 of Fig. 1; Fig. 5 is a transverse section taken on the line 5—5 of Fig. 4; Fig. 6 is a section taken on the line 6—6 of Fig. 5; Fig. 35 7 is a section taken on the line 7—7 of Fig. 3; and Fig. 8 is a detail view of the connection between the agitator and its actuating shaft.

40 In these drawings I have illustrated one embodiment of my invention but it will be understood that this particular embodiment has been chosen for the purpose of illustration only and that the mechanism may take 45 various forms without departing from the spirit of the invention.

The machine shown in these drawings 50 comprises a tub 1 which is supported by a pedestal 2, the latter being here shown as formed of sheet metal. Interposed between the pedestal 2 and the tub is a gear box, indicated as a whole by the reference number 3, which serves to connect the tub with the pedestal. This gear box preferably 55 comprises an inner end portion 4 which, in the present machine, is substantially cylindrical

in shape and is rigidly secured to the upper end of the pedestal 2 by screws 5. Preferably the part 4 of the gear box is provided at its lower edge by a flange 6 which overlaps the upper end of the pedestal and not only reinforces the connection between the two parts but conceals the joint and gives the structure a more finished appearance. The upper end of the part 4 of the gear box is 60 open and, in the present instance, is slightly enlarged, as shown at 7. The bottom wall of the tub, which is preferably of sheet metal, rests upon the upper end of the gear box and has an opening in line with the gear box, as shown at 8. The tub is secured to the gear box by means of a plate or closure 65 9 which overlaps that portion of the bottom of the tub adjacent to the opening and is secured to the gear box by means of screws 10 which extend through the closure plate, the bottom of the tub and into lugs 11 formed within the upper end of the gear box. If desired, packing may be interposed 70 between the closure plate and the bottom of the tub to provide a leak-proof joint. The closure plate when in position forms part of the bottom of the tub and also carries an upwardly extending tubular member 12 which extends to a point spaced a short 75 distance from the top of the tub and which may, if desired, extend into the gear box, as shown at 13. Rotatably mounted on the tubular member 12 is an agitator comprising a disk-like base 14 and an upwardly extending tubular portion 15 which is mounted 80 about the tubular member 12 for rotation with relation thereto. Fins or blades 16 are connected at their lower edges with the base 14 and at their inner edges with the 85 tubular part 15 of the agitator. Mounted within the fixed tubular member 12 is a shaft 17 the upper end of which projects above the tubular member 12 and has rigidly secured thereto a collar or short sleeve 18, the upper portion of which is provided 90 on opposite sides thereof with downwardly tapered notches 19. Extending through and rigidly secured to the upper part of the tubular portion 15 of the agitator is a pin 100 20 adapted to enter the notches 19 and of such a diameter that it will engage the converging edges of the notches with a wedging action. Thus the agitator may be readily removed from or applied to the tubular member 12, and connected with the shaft, 105 21 by simply lifting it off or slipping it on the

tubular member. The pin 20 enters the notches in the collar 18 and provides a firm driving connection therewith which, because of the wedging action of the pin in the 5 notches, will have no play and will take up automatically any wear which may occur, thus preventing all lost motion between the shaft and the agitator. The upper end of the tubular part of the agitator is closed 10 by a cap 21. The lower end of the shaft 17 extends into the gear box beyond the lower end of the part 13 of the tubular member and is, in the present instance, seated in a step bearing 22 carried by a transverse member 23 arranged within and preferably formed integral with the gear box. Rigidly secured to the shaft within the gear box is a pinion 24.

The gear box 4 preferably consists of a 20 one-piece casing which, in the present instance, is formed by casting and this casing is of such a character and so shaped that the driving mechanism may be readily inserted therein and assembled. In the construction here shown, the casing comprises the cylindrical portion 4 and has extending laterally from the upper part of that cylindrical portion an extension or outer portion 25, the outer end of which is slightly enlarged, as shown at 26, and has its lower side closed by a removable plate or cap 27. The driving mechanism, in the present instance, comprises two units and the casing of the gear box is of such a character that 30 one of these units may be inserted through the open upper end of the inner portion 4 thereof, before the tub is placed in position thereon, and that the other of the gear units may be inserted through the opening in the outer portion of the casing and operatively connected with the first unit. The first mentioned unit of the driving mechanism may be characterized as a pitman unit and it comprises an elongated actuating member or pitman 28 having at its outer end an eccentric strap 29. Pivotally connected with the inner end of the pitman is a segmental gear 30 which is pivotally mounted within the gear casing, by means of a pivot pin 30, and 40 meshes with the pinion 24 on the shaft 17. In assembling the mechanism the toothed segment is swung about its pivotal connection with the pitman to a position above the latter and the casing of the gear box is so shaped that when the pitman unit is in this position it may be inserted through the open upper end of the part 4 of the casing into the lateral portion 25 thereof, the length of the pitman being such that the eccentric strap 50 will be located in a position above the opening in the outer portion of the casing. In order that the pivot pin 31 may be inserted through the toothed segment after the latter has been placed within the casing 60 of the gear box the lateral portion of the cas-

ing is provided in its lower wall with a boss 32, the outer end of which is closed by a plate 33 and in which is mounted a bushing or bearing 34 to receive the lower end of the pivot pin 31. The upper wall of the casing is provided with an opening 35 in line with the bearing 34 and of such a diameter that a tool may be inserted therethrough to face or machine the inner edge of the boss to provide a bearing surface. The opening 35 in the casing is closed by a cap 36 having a hollow extension or boss 37 extending into the opening and carrying a bushing or bearing 38 for the upper portion of the shaft. After the pitman unit has been inserted in the casing the hub of the toothed segment is moved into line with the bearing 34, the pivot pin 31 inserted through the hub and into the lower bearing and the cap 36 then placed in position with the bearing 38 about the upper end of the pivot pin. The hub of the segment is secured to the pivot pin by a set screw 39, the pivot pin being provided with a circumferential groove 40 to receive the end of the set screw and prevent the longitudinal movement of the pivot pin with relation to the toothed segment and also to permit the toothed segment to be secured to the pivot pin in any position circumferentially thereof, thus avoiding the necessity of bringing the set screw into line with a particular part of the pivot pin. The set screw is so arranged in the hub of the toothed segment that it may be moved into line with the part 4 of the casing so as to be readily accessible to the operator.

Mounted in the outer portion of the gear casing is a shaft unit which is operatively connected with the pitman unit and with a source of power. As here shown, this shaft unit comprises a vertical shaft 41 journaled in a bearing 42, formed in an upper extension 43 of the casing, and seated at its lower end in a step bearing 44 in the closure plate 27. Loosely mounted on the shaft 41 is an eccentric 45 which fits within the eccentric strap 29 of the pitman. Suitable clutch mechanism is mounted on the shaft to connect the eccentric with and disconnect the same from the shaft. As here shown, a clutch member 46 is rotatably mounted on the shaft immediately above the eccentric and is rigidly secured to the latter by screws 47. The clutch member 46 and the eccentric are held against upward movement by means of a collar 48 which is rigidly secured to the shaft, preferably by a pin, and is, in the present instance, seated in an annular recess in the clutch member. The eccentric and clutch member are held against downward movement by a worm gear 49 which is rigidly secured to the shaft 41. A second clutch member 50 is slidably mounted on the shaft above the clutch member 46 and is held against rotation thereon, as by means of a 100

spline 51. The clutch member 50 has a circumferential groove 52 in which is mounted a shifting yoke 53. Connected with this yoke is an actuating rod 54 which is slidably mounted in a bearing 55 in the part 25 of the casing.

In assembling this part of the mechanism the shaft unit, including the shaft 41, the eccentric 45, the clutch members 46 and 50 and the clutch shifting device, and, if desired, the worm gear 49, are assembled outside of the casing and inserted in the casing as a unit. The eccentric strap 29 of the pitman is of such a diameter that the clutch 15 and its actuating device will pass through the same and the bearing 42 is arranged directly above the lower opening in the casing, thus the shaft and the parts carried thereby may be passed through the opening in the 23 lower end of the casing and through the eccentric strap, the shaft 41 being inserted in the bearing 42, the actuating rod 54 being inserted in the bearing 55, and the eccentric being inserted in the eccentric strap. The 23 closure plate 27 is then placed in position and the several parts thus retained in their operative positions.

The worm gear 49 is driven by a worm 56 which is mounted in an offset part 57 of the 30 casing and carried by a shaft 58, one end of which is mounted in a bearing 59 and the other end of which is supported in a bearing 60, this latter bearing being threaded into the open end of the part 57 of the casing 35 and a cap 61 being rigidly secured to that end of the casing beyond the bearing and provided with a stuffing box 62. This shaft is also provided with collars 63 to engage the respective bearings and take the end 40 thrust on the shaft. The worm shaft 58 may be driven from any suitable source of power. It is here shown as connected with an electric motor 64 which is mounted on a bracket 65 carried by the inner portion 4 of the gear 45 box. It will be noted that the portion 4 of the gear box extends downwardly beyond the laterally extending part 25 thereof and thus provides ample space for mounting the motor, and the gear box being a casting 50 forms a much firmer support for the electric motor than would the sheet metal pedestal 2, although obviously the motor may be mounted on any suitable part of the mechanism.

55 The vertical shaft 41 has an upwardly extending portion 66, which may be formed integral with or separately from the main portion of the shaft and this upper portion of the shaft extends through a tubular housing 67 projecting upwardly from the part 60 43 of the gear box casing and having at 68 the usual support for the wringer. The part 66 of the shaft may be connected with the wringer in the usual or any suitable manner but inasmuch as the wringer and its con-

nections form no part of the present invention they are not illustrated. The clutch actuating rod 54 extends upwardly alongside the tubular housing 67 and is slidably mounted at its upper end in a guideway 69 formed in the side of the wringer support. The upper end of the rod, within the guideway 69, is provided with teeth 70, these teeth preferably extending entirely about the rod so as to avoid the necessity of the rod 75 being located in an exact circumferential position. A pinion 71, mounted in a suitable housing carried by the supporting member or casting 68 at the top of the housing 67, meshes with the rack teeth 70 on the actuating rod 54 and suitable means are provided for actuating this pinion to shift the clutch. In the present construction the pinion has a stud 72 extending axially therefrom and mounted in a member 73 which is rotatably 80 mounted in a bearing 74 and is provided with a handle 75 by means of which it may be manipulated. As here shown, the stud 72 has a circumferential groove 76 to receive the inner end of a set screw 77 mounted in 85 the rotatable member 73. The groove permits the location of the pinion in any desired position with relation to the rotatable member and the set screw engages the base of the housing to rigidly connect the parts 90 one to the other. The rotatable member 73 is also provided with a circumferential groove, as shown at 78, and a spring pressed plunger 79 extends into this groove to retain the rotatable member within the bearing and 100 permit the same to have rotatory movement. The rotatable member has in the base of the groove 78 two or more recesses 80 spaced apart and adapted to receive a tapered end of the plunger 79 to yieldably retain the 105 member 73 against rotation. Thus in shifting the clutch pressure is applied to the handle 75 sufficient to overcome the resistance of the yieldable plunger or detent 79 and the rotatable member 73 and pinion 71 are 110 rotated until the plunger enters the second recess and thus offers additional resistance to the movement of the handle, which indicates that the clutch has been completely shifted. The adjustable connections between the rotatable member 73 and the pinion and the bearing permit of the handle being adjusted with relation to the clutch member to take up any lost motion and to compensate for the 115 wear on the clutch members.

While I have shown and described one embodiment of my invention I wish it to be understood that I do not desire to be limited to the details thereof as various modifications may occur to a person skilled in the 125 art.

Having now fully described my invention, what I claim as new and desire to secure by Letters Patent, is:

1. In a clothes washing machine, a tub, a 130

pedestal having a relatively narrow portion arranged centrally of and in supporting relation to said tub, a gear box interposed between said pedestal and said tub and having 5 a laterally extending tubular portion, an agitator mounted in said tub, a shaft connected with said agitator and extending into said gear box, driving mechanism in said gear box having at its inner end means for connecting the same with said shaft and having at its outer end means for connecting the same with a source of power, said gear box comprising a casing formed in one piece and having openings near the ends thereof 10 through which said driving mechanism may be inserted and assembled therein.

2. In a clothes washing machine, a pedestal having an upwardly extending portion of relatively small diameter, a tub supported 20 by said pedestal, an agitator in said tub, a shaft to actuate said agitator, a gear box comprising a one piece casing having a part interposed between said tub and said pedestal, said part of said casing having an opening 25 at its upper end arranged to be closed when said tub is in position thereon, said casing also having a laterally extending tubular part, the outer end of which has an opening, a removable closure for the last 30 mentioned opening, and driving mechanism for said shaft comprising a plurality of parts adapted to be inserted through the respective openings and connected one with the other within said casing.

3. In a clothes washing machine, a pedestal, a tub supported by said pedestal, an agitator shaft extending into said tub, a gear box comprising a one piece casing having a part interposed between said tub and 40 said pedestal, said part of said casing having an opening at its upper end arranged to be closed when said tub is in position thereon, said casing also having a laterally extending part, the outer end of which has 45 an opening, a removable closure for the last mentioned opening, an elongated actuating member having means for operatively connecting the same with said agitator shaft, said casing being so shaped that said member 50 may be inserted through the first mentioned opening into said lateral part, a second shaft, said casing having a bearing into which said second shaft may be inserted through the opening in the outer end 55 portion thereof, and means for operatively connecting said actuating member with said second shaft after said parts have been inserted in said casing.

4. In a clothes washing machine, a pedestal, a tub supported by said pedestal, an agitator shaft extending into said tub, a gear box comprising a one piece casing having a part interposed between said tub and 60 said pedestal, said part of said casing having an opening at its upper end arranged to

be closed when said tub is in position thereon, said casing also having a laterally extending part, the outer end of which has an opening, a removable closure for the last mentioned opening, a pitman having at one 70 end thereof means for connecting the same with said agitator shaft and having at the other end thereof an eccentric strap, said casing being so shaped that said pitman may be inserted through the first mentioned opening into the lateral part thereof, a second shaft, said casing having a bearing so arranged that said second shaft may be passed through the opening in the outer portion of 75 said casing and through said eccentric strap into said bearing, and an eccentric mounted on said second shaft and movable through the last mentioned opening into said eccentric strap.

5. In a clothes washing machine, a pedestal, a tub supported by said pedestal, an agitator shaft extending into said tub, a gear box comprising an integral casing having a part interposed between said tub and said pedestal, said part of said casing having an opening at its upper end arranged to be closed when said tub is in position thereon, said casing also having a laterally extending part, the outer end of which has an opening, a removable closure for the last 80 mentioned opening, driving mechanism comprising two units, said casing being so shaped that one of said units may be inserted therein through the first mentioned opening, said unit having means for operatively connecting the same with said agitator shaft, said casing being so shaped that the second unit may be passed through the last mentioned opening and operatively mounted in said casing, the two units having means for operatively connecting them one to the other within said casing, and means for operatively connecting said second unit with a source of power.

6. In a clothes washing machine, a pedestal, a tub supported by said pedestal, an agitator shaft extending into said tub, a gear box comprising an integral casing having a part interposed between said tub and said pedestal, said part of said casing having an opening at its upper end arranged to be closed when said tub is in position thereon, said casing also having a laterally extending part, the outer end of which has an opening, a removable closure for the last 110 mentioned opening, driving mechanism comprising a pitman unit and a shaft unit, said pitman unit including a pitman having an eccentric strap at one end thereof and having at the other end thereof means for connecting it with said agitator shaft, said casing being so shaped that said pitman unit may be inserted through the first mentioned opening into the lateral part of said casing, said shaft unit including a shaft, an ec- 115 120 125 130

- centric rotatably mounted on said shaft, and clutch mechanism mounted on said shaft to connect the same with said eccentric, said casing having a bearing so arranged that 5 said shaft unit may be passed through the last mentioned opening in said casing and through said eccentric strap to insert the shaft thereof in said bearing and to insert said eccentric in said eccentric strap, and 10 means for connecting said eccentric with a source of power.
7. In a clothes washing machine, a pedestal, a tub supported by said pedestal, an agitator shaft extending into said tub, a gear 15 box comprising an integral casing having a part interposed between said tub and said pedestal, said part of said casing having an opening at its upper end arranged to be closed when said tub is in position thereon, said casing also having a laterally extending part, the outer end of which has an opening, a removable closure for the last mentioned opening, a pitman unit comprising a pitman having an eccentric strap at 20 one end thereof and a toothed segment pivotally connected with the other end thereof, said casing being so shaped that said pitman unit may be inserted through the first mentioned opening into said lateral part thereof, 25 means for pivotally mounting said segment in said casing, a pinion connected with said agitator shaft and arranged in said casing to mesh with said toothed segment, a second shaft, an eccentric mounted on said second 30 shaft, said casing having a bearing so arranged that said second shaft and said eccentric may be passed through the opening in said outer part of said casing and inserted respectively in said bearing and said 35 eccentric strap, and means for operatively connecting said eccentric with a source of power.
8. In a clothes washing machine, a pedestal, a tub supported by said pedestal, an agitator shaft extending into said tub, a gear 40 box comprising an integral casing having a part interposed between said tub and said pedestal, said part of said casing having an opening at its upper end arranged to be closed when said tub is in position thereon, said casing also having a laterally extending part, the outer end of which has an opening, a removable closure for the last 45 mentioned opening, driving mechanism comprising a pitman unit and a shaft unit, said pitman unit including a pitman having an eccentric strap at one end thereof and having at the other end thereof means for connecting it with said agitator shaft, said casing being so shaped that said pitman unit 50 may be inserted through the opening in the upper end of the first mentioned part of said casing into the lateral part thereof, said shaft unit including a shaft, an eccentric rotatably mounted on said shaft, clutch 55 mechanism mounted on said shaft to connect the same with said eccentric and an operating rod for said clutch mechanism, said casing having bearings for the shaft and the clutch operating rod of said shaft unit, said 60 bearings being so arranged that said shaft unit may be passed through the opening in the outer part of said casing and through said eccentric strap to insert said shaft and said actuating rod in the respective bearings 65 and to insert said eccentric in said eccentric strap, means for operatively connecting said eccentric with a source of power, said clutch operating rod having a series of teeth near the upper end thereof, a pinion meshing 70
- segment and said bearing, a bearing mounted in the last mentioned opening to receive the adjacent end of said pivot pin, a pinion connected with said agitator shaft and arranged in said casing to mesh with said toothed segment, a second shaft, an eccentric mounted on said second shaft, said casing having a bearing so arranged that said second shaft and said eccentric may be passed through the opening in the outer part of said casing and inserted respectively in said bearing and said eccentric strap, and means for operatively connecting said eccentric with a source of power.
9. In a clothes washing machine comprising a tub and a pedestal to support the same, a one piece gear casing comprising a vertically extending portion interposed between said pedestal and said tub and having an open upper end adapted to be closed by said tub, said gear casing also having a laterally extending tubular part provided in its lower portion with an opening and having a vertical bearing arranged in line with said opening, a closure for said opening, and driving mechanism adapted to be inserted in said gear casing through said openings.
10. In a clothes washing machine, a pedestal, a tub supported by said pedestal, an agitator shaft extending into said tub, a gear 80 box comprising an integral casing having a part interposed between said tub and said pedestal, said part of said casing having an opening at its upper end arranged to be closed when said tub is in position thereon, said casing also having a laterally extending part, the outer end of which has an opening, a removable closure for the last 85 mentioned opening, driving mechanism comprising a pitman unit and a shaft unit, said pitman unit including a pitman having an eccentric strap at one end thereof and having at the other end thereof means for connecting it with said agitator shaft, said casing being so shaped that said pitman unit 90 may be inserted through the opening in the upper end of the first mentioned part of said casing into the lateral part thereof, said shaft unit including a shaft, an eccentric rotatably mounted on said shaft, clutch 95 mechanism mounted on said shaft to connect the same with said eccentric and an operating rod for said clutch mechanism, said casing having bearings for the shaft and the clutch operating rod of said shaft unit, said 100 bearings being so arranged that said shaft unit may be passed through the opening in the outer part of said casing and through said eccentric strap to insert said shaft and said actuating rod in the respective bearings 105 and to insert said eccentric in said eccentric strap, means for operatively connecting said eccentric with a source of power, said clutch operating rod having a series of teeth near the upper end thereof, a pinion meshing 110
11. In a clothes washing machine, a pedestal, a tub supported by said pedestal, an agitator shaft extending into said tub, a gear box comprising an integral casing having a part interposed between said tub and said pedestal, said part of said casing having an opening at its upper end arranged to be closed when said tub is in position thereon, said casing also having a laterally extending part, the outer end of which has an opening, a removable closure for the last 115 mentioned opening, driving mechanism comprising a pitman unit and a shaft unit, said pitman unit including a pitman having an eccentric strap at one end thereof and having at the other end thereof means for connecting it with said agitator shaft, said casing being so shaped that said pitman unit 120 may be inserted through the opening in the upper end of the first mentioned part of said casing into the lateral part thereof, said shaft unit including a shaft, an eccentric rotatably mounted on said shaft, clutch mechanism mounted on said shaft to connect the same with said eccentric and an operating rod for said clutch mechanism, said casing having bearings for the shaft and the clutch operating rod of said shaft unit, said bearings being so arranged that said shaft unit may be passed through the opening in the outer part of said casing and through said eccentric strap to insert said shaft and said actuating rod in the respective bearings 125 and to insert said eccentric in said eccentric strap, means for operatively connecting said eccentric with a source of power, said clutch operating rod having a series of teeth near the upper end thereof, a pinion meshing 130

with said teeth, and a rotatable member connected with said pinion and provided with a handle.

11. In a clothes washing machine of the character described, comprising a tub, an agitator shaft extending into said tub, a driving shaft, an actuating member interposed between said driving shaft and said agitator shaft, a clutch to control the connection between said connecting member and said driving shaft, and a clutch operating rod connected at its lower end with said clutch mechanism, a guide for the upper end of said actuating rod, that part of said actuating rod located within said guide having a longitudinally arranged series of teeth, a housing opening into said guideway, a pinion rotatably mounted in said housing and meshing with the teeth on said rod, an actuating member rotatably mounted in said housing and rigidly connected with said pinion, and a handle for imparting rotatory movement to said actuating member.

12. In a clothes washing machine comprising a tub, a pedestal to support said tub, a gear casing having a part interposed between said pedestal and said tub, an agitator shaft mounted in said tub and extending into said gear casing, a pitman mounted in said gear casing, operatively connected with said agitator shaft and having an eccentric strap at the outer end thereof, a vertical shaft mounted in the outer portion of said gear casing, an eccentric loosely mounted on said shaft and arranged within said eccentric strap, a tubular housing extending upwardly from the outer part of

said gear casing, the last mentioned shaft having a part extending through said tubular housing, a supporting structure at the upper end of said tubular housing having a vertical guideway, a clutch to control the connection of said eccentric with the last mentioned shaft, an operating rod connected at its lower end with said clutch mechanism and having its upper end mounted in said guideway and provided with a series of teeth, a housing carried by said supporting structure and opening into said guideway, a pinion mounted in said housing and meshing with the teeth of said rod, an actuating member rotatably mounted in said housing and rigidly connected with said pinion, and a handle for imparting movement to said actuating member.

13. In a clothes washing machine, a tub, a tubular member extending upwardly from the base of said tub, a shaft rotatably mounted in said tubular member and extending beyond the upper end thereof, a collar rigidly secured to said shaft, extending beyond the upper end thereof and having downwardly tapered notches in opposite sides thereof, an agitator mounted in said tub and comprising a tubular member mounted about the first mentioned tubular member, and a pin extending through the upper part of the tubular member of said agitator, and adapted to enter the notches in said collar and engage the edges thereof with a wedging action.

In testimony whereof, I affix my signature hereto.

LOVELL A. HERSH.
